FIREDOOR CONSTRUCTION FOR STOKERS

Charles J. Surdy, Tuckahoe, N. Y., assignor to
The Standard Stoker Company, Incorporated,
a corporation of Delaware

Application October 18, 1933, Serial No. 694,019

7 Claims. (Cl. 110—101)

My invention relates to improvements in fire-door construction used in connection with stokers which feed through the handfiring opening of a furnace.

5 In stokers which feed through the usual handfiring opening of a furnace, the upper end of the stoker discharge conduit constitutes a frame for supporting the firedoor. The firedoor frame embraces the firing opening and extends rearwardly from the furnace wall a distance sufficient to surmount the upper end of the stoker discharge conduit. In certain instances the firedoor frame extends rearward of the firing opening in the furnace wall a distance such that a long 10 tunnel is formed through which access into the furnace is gained. When the condition of the fire is such that it is necessary for the fireman to use a hook or a rake for the purpose of breaking up or removing a clinker, or to make other adjustments in the firebed, considerable difficulties are experienced in performing these duties. These 15 difficulties are present especially when it is necessary to reach the corners of the furnace immediately at each side of the firedoor opening.

20 It is the object of this invention to obviate these difficulties in a simple and efficient manner by the provision of supplemental or auxiliary doors, one in each side wall of the firedoor frame, as will be apparent from the following description when 25 it is read in connection with the drawing which illustrate the invention adapted for use with a locomotive stoker, and in which

Figure 1 is a side elevational view of the stoker embodying my invention with the locomotive furnace in section,

Figure 2 is a rear elevational view of the structure shown in Figure 1, with portions removed and others in section, and

Figure 3 is a sectional view taken on the line 3—3 of Figure 2 with one of the auxiliary doors opened.

On the drawing, 10 represents the locomotive, 11 the furnace or firebox thereof and 12 the backwall which has a firing opening 13 therethrough. 45 At 14 I have generally indicated a stoker which includes a discharge conduit 15, in communication with the firing opening through the upwardly opening mouth 16. A flange 17 is formed with the discharge conduit 15 and bolts 18 passing 50 through the flange form the means for securing the conduit to the backwall 12. If found necessary, a bracket such as 19 may support the conduit 15 from the furnace mud ring 20.

Surmounting the mouth 16 of the conduit 15 is a frame 21, which embraces that portion of the

firing opening 13 immediately above the mouth 16, to form an upward continuation of the stoker discharge conduit 15. A flange 22, is also formed with the frame 21. Bolts 23 are passed through this flange and secure the frame to the backwall 12. If desirable, the frame 21 could be formed integrally with conduit 15 and in this case the flange 22 would then be an upward continuation of the flange 17. A firedoor 24 is operatively mounted on the frame 21 at that end thereof 60 remote from the flange 22 and preferably directly opposite the firing opening 13. It is necessary that the fuel, as it is urged through the conduit 15 by the screw 25, be delivered to the distributing means 26 in a free and loose form. In order to accomplish this result, the conduit mouth 16 is of substantial proportions, such that the frame 21 necessarily extends rearward of the backwall 12 a considerable distance. The frame 21 forms, in effect, a tunnel 27 through which access into the 65 firebox 11 is gained.

In certain instances, this tunnel formation has been found to be objectionable because the rear corners of the firebox are not within reach of the fireman's hook or rake whenever it is necessary to remove and break up clinkers, or, to smooth out a bank in the fire at these points. By my present invention I obviate these difficulties in a very simple and efficient manner. At each sidewall 70 28 of the frame 21, I have formed a recess such as 29, extending from the rearward edge 30 of the frame toward the flange 22. Each of these recesses 29 is normally closed by an auxiliary door 31 which is hinged to the frame 21 as at 32. I 75 hinge these auxiliary doors to the frame at their lower ends and employ eccentric latches 33 at their upper ends to retain the doors in their closed position. Lugs 34, formed with the doors 31 engage the frame 21 and prevent movement of the doors into the tunnel 27. By hinging the auxiliary doors at their lower ends, no added means is necessary to keep these doors in their opened position.

When the locomotive is in normal operation, the firedoor 24 is closed and the stoker 14 feeds fuel to the distributing means 26 for projection over the fire by fluid means. However, when a bank or clinker forms in either rear corner of the firebox, the firedoor 24 is opened and the proper auxiliary door 31 is also swung open. The fireman then passes a hook or rake 35 through the tunnel 27 and the firing opening 13 and either smooths out the bank or removes or breaks up the clinkers. It will be observed from Figure 3 that the recesses 29 permit the rake or hook 35 to be 100 105 110

angled closely to the backwall 12 and thus the rear corners of the firebox are easily reached. From the foregoing, it is apparent that I have devised a simple and a highly advantageous construction for use in connection with furnace fire-doors.

I claim:

1. In combination, a furnace having a wall with a firing opening therein, a frame secured to said furnace wall, said frame having walls which extend rearwardly from said furnace wall, the rear edges of said walls defining an opening opposite said firing opening, at least one of said walls being provided with a recess extending from the rear edge of such wall toward the furnace wall, a firedoor supported from said frame and closing the opening defined by the rear edges of said walls, and an auxiliary door closing said recess.

2. In combination, a furnace having a wall with a firing opening therein, a frame secured to said furnace wall, said frame having walls which extend rearwardly from said furnace wall, the rear edges of said walls defining an opening opposite said firing opening, opposite walls of said frame being provided each with a recess extending from the rear edge of such wall toward the furnace wall, a firedoor supported from said frame and closing the opening defined by the rear edges of said walls, and an auxiliary door closing each of said recesses.

3. In combination, a furnace having a wall with a firing opening therein, a frame secured to said furnace wall, said frame having walls which extend rearwardly from said furnace wall, the rear edges of said walls lying in a common plane and defining an opening opposite said firing opening, at least one of said walls being provided with a recess extending from the rear edge of such wall toward the furnace wall, a firedoor supported from said frame and closing the opening defined by the rear edges of said walls, and an auxiliary door closing said recess.

4. In combination, a furnace having a wall with a firing opening therein, a frame secured to said furnace wall, said frame having walls which extend rearwardly from said furnace wall, the rear edges of said walls lying in a common plane and defining an opening opposite said firing opening, opposite walls of said frame being provided each with a recess extending from the rear edge of

such wall toward the furnace wall, a firedoor supported from said frame and closing the opening defined by the rear edges of said walls, and an auxiliary door closing each of said recesses.

5. In combination with a locomotive firebox having a backwall with a firing opening therein, a stoker discharge conduit arranged to feed through said firing opening, said discharge conduit including an upwardly opening mouth, a frame embracing said firing opening and forming an upward extension of said stoker discharge conduit, said frame having walls, including side walls, extending rearwardly from said backwall, the rear edges of such walls defining an opening opposite said firing opening, each of the side walls being provided with a recess extending from the rear edges of said walls toward the backwall, a firedoor supported from said frame and closing the opening defined by the rear edges of the walls, and an auxiliary door closing the recess in each side wall.

6. In combination with a locomotive firebox having a backwall with a firing opening therein, a stoker discharge conduit arranged to feed through said firing opening, said discharge conduit including an upwardly opening mouth, a frame embracing said firing opening and forming an upward extension of said stoker discharge conduit, said frame having walls, including side walls, extending rearwardly from said backwall, the rear edges of such walls lying in a common plane and defining an opening opposite said firing opening, each of the side walls being provided with a recess extending from the rear edges of said walls toward the backwall, a firedoor supported from said frame and closing the opening defined by the rear edges of the walls, and an auxiliary door closing the recess in each side wall.

7. In combination, a furnace having a wall with a firing opening therein, a frame secured to said furnace wall, said frame having walls which extend rearwardly from said furnace wall, the rearward edge portions of said walls defining an opening opposite said firing opening, at least one of said walls being provided with a recess extending from the rear edge of such wall toward the furnace wall and a movable door covering said recess.
